FINISHING MACHINE

Warren J. Heldenbrand, Muncie, Ind.

Application April 13, 1948, Serial No. 21,631

5 Claims. (Cl. 51—84)

1

This invention relates to improvements in machines intended for finishing of articles of flat ware. It has especial reference to a machine of this type wherein the ware is subjected to the action of opposed buffs.

Incidental to the fact that contours of articles as forks, spoons and the like, are sinuous, a difficulty encountered in the use of machines as hitherto devised is, that the effect of the buffs upon said contours is not uniform, and the finish imparted by the use of such machines is unsatisfactory.

Advantages desired in the procedure of finishing articles of the above description are, that the finish must be consistent with the quality of the article, and with the contours thereof, and it must be so imparted that it is uniform in quality throughout the full extent of the surfaces treated; and also, that the articles may be treated in quantity and with efficiency making for economy and minimum cost.

To provide a machine for attaining the above named advantages is the object broadly stated, of my invention. The said general object, and also certain other and specific aims of my invention as will presently appear, are accomplished by, and my invention is embodied in the new construction, combination and arrangement of parts described in the following specification and illustrated in the accompanying drawings.

The several parts of my invention, as they appear in the different views in the drawings are identified by suitable characters of reference. In the said drawings:

Figure 1 is a front view of my new vertical finishing machine.

Figure 2 is a top plan view of said machine, a portion of the top of the frame broken away, and the cross beam being shown partially in cross section.

Figure 3 is a side view in the direction of arrow 3 in Figure 1, a portion of the obverse side of the hood being broken away disclosing to view the ends of the buff carriages.

Figure 4 is a rear view in the direction of arrow 4 in Figure 3, indicating the relative locations of the several hydraulic, electric and compressed air units, and piping and wiring therefor being indicated fragmentarily.

Figure 5 is a sectional top plan view in direction of arrow 5 on broken line 5—5 in Figure 4.

Figure 6 is an enlarged front view of the machine, the hood sections removed, and a portion of the frame of the machine shown in cross section.

2

Figure 7 is an enlarged top plan view taken on broken line 7—7 in the direction of arrow 7 in Figure 3, the suspensor devices on the face plate being broken away.

Figure 8 is an enlarged side view of the upper portion of the machine, being shown in cross-section on broken line 8—8, and the lower portion of the machine being shown in cross-sections on line 8a—8a, in the direction of arrow 8 in Figure 7.

Figure 9 is a vertical cross-section view on broken line 9—9 in the direction of arrow 9 in Figure 6.

Figure 10 is a sectional top plan view on broken line 10—10 in Figure 3.

Figure 11 is a sectional top plan view on broken line 11—11 in Figure 8, to show the lever wrists that cooperate with the templets.

Figure 12 is a vertical cross section view on broken line 12—12 in Figure 8, to show the inner face of the rear buff carriage and discharge chute.

Figure 13 is a vertical longitudinal sectional view on broken line 13—13 in direction of arrow 13 in Figure 11, to show the left-hand racks and pinions.

Figure 14 is a vertical longitudinal sectional view on broken line 14—14, in the direction of arrow 14 in Figure 11, to show the right-hand racks and pinions.

Figure 15 is an enlarged detail view of the templet cross head, and contour templet connected therewith.

Figure 16 is an end view of Figure 15, in the direction of arrow 16.

Figure 17 is a detail plan view of the head or chuck end of one buff mandrel, and of the tail end of the other buff mandrel.

Figure 18 is an enlarged detail side view of the divided bearing for tail journal of buff mandrel.

Figure 19 is a detail side view of vertical bar and trips 25 carried by the cross beam of the machine, and as shown in Figure 4.

Figure 20 is a top plan view of Figure 19.

Figure 21 is an end view of pilot valve and dogs shown in Figure 19.

Figure 22 is a detached top plan view of left hand end portion of carrier plate 101 and the suspensor bracket fixture attached thereto.

Figure 23 is a vertical cross-section view on the broken line 23—23 in Figure 22.

Figure 24 is a side view of work rack adapted for the retention of ware, as forks and the like.

Figure 25 is an enlarged cross-section view on broken line 25—25 in Figure 24.

Figure 26 is an enlarged view of parts indicated in Figure 24.

Figure 27 is a view indicating the appearance of an unfinished fork, an article of the kind for which a work rack as illustrated in Figure 24 is especially adapted.

Figure 28 is a side view indicating the appearance of a work rack of modified form and adapted for an article such as a spoon.

Figure 29 is a top plan view on broken line 29—29 of Figure 28.

Figure 30 is a view in the direction of arrow 30 in Figure 28.

Figure 31 is a diagrammatic view indicating the hydraulic system through which the power is supplied and controlled for operating the cross beam, face plate and carrier plate.

Figure 32 is a diagrammatic view indicating the compressed air system through which power is supplied and controlled for operating the cylinders having connection with the buff carriages.

Figure 33 is a diagram of the electric system for operating the motors.

The frame of the machine comprises a deck plate 31 preferably of steel and of suitable plan formation (as illustrated in Figure 7) integrated with girders 32, supported by legs 33, and suitably stayed as by braces 36. Upon said deck is a housing 39 upon which is integrated a towerlike structure embodying spaced uprights 41 and 42.

As indicated in Figures 4, 11, 13 and 14 of the drawings, a rack rod 44 (at left hand side of the machine) slidable vertically in a suitable guideway therefor in column 45 meshes with a pinion 46 that is interconnected by a common axle to a similar pinion 46a. A rack rod 54 (at right hand side of the machine) slidable vertically in a suitable guideway therefor in column 55 meshes with a pinion 56 that is interconnected by a common axle to a similar pinion 56a. The said rack rods 44 and 54 the upper ends of which are threaded, and the said pinions, will presently be further referred to.

Secured to an upright back plate 48 that is integrated with ribs 49 which extend from the rear sides of said uprights 41 and 42, is a vertical hydraulic cylinder 51, the inlet and exhaust pipes therefor designated 52 and 53 respectively. See Figure 31. The outward end portion of the upwardly directed piston rod 59 of said cylinder is threaded.

A cross beam 61 with rearwardly offset median portion 62 embodies at its ends, rearwardly directed brackets 64 and 74 each having a vertical bore. In the bores of these brackets are received the upper end portions of the aforesaid rack rods 44 and 54 and which are secured in the positions to which they are adjusted, by lock nuts 65.

The piston rod 59 of said vertical cylinder is secured as by lug fixture 67 to the said cross beam, as indicated in Figure 9. Secured to the rear face of said cross beam, at each side of the offset median portion thereof, and arranged one above the other, are brackets 70 and 71 each provided with a vertical bore. See Figure 3 and Figure 8. Received in the bores of these brackets are vertical slide rods 72 which are secured at their ends to anchor blocks 73 and 75 that in turn are secured to the faces of the uprights 41 and 42 as shown in Figure 8. The said cross beam 61 so arranged in connection with the slide rods 72 and with the piston of the said vertical cylinder

51 is, together with the rack rods 44 and 54, vertically reciprocable.

Secured to the frontal face of the rearwardly offset median portion 62 of said cross beam, is 5 a horizontal hydraulic cylinder 81 through whose opposite ends pass the piston rods 82 and 83 the outward ends of which are threaded as indicated in Figure 10. Secured to the ends of said piston rods as by head blocks 84 is a vertical rectangular face plate 88. At positions equidistant from the vertical center of the rear side of said face plate are brackets 90, one above the other (see Figures 7 and 8), each with a horizontal bore. Transverse horizontal slide rods 91 received in the bores 10 of said brackets have their ends secured to anchor blocks 94 which in turn are secured to the frontal face of the said cross beam 61. Projecting forwardly from the top portion of said face plate 88 is a lug 95 (as indicated in Figure 3 and Figure 8) through which is threaded a vertical adjusting screw 96. The said face plate 88 so arranged and interconnected with the pistons of the horizontal cylinder 81 (Figure 10) and with the slide rods 91 (Figure 7) is transversely reciprocable.

An elongated carrier plate 101 (see Figures 1 and 6) has a frontal lug 102 with threaded hole in which the said screw 96 is received. Slide blocks 103 (see Figure 10) that are provided at the rear side of the end portions of said carrier plate engage the ends of said face plate 88. The said carrier plate so arranged is capable of being disposed in and held at vertically adjusted position on the said face plate.

On the frontal face of said carrier plate 101 at positions equidistant from its vertical center, are brackets 105 and 106. The leg of one of these brackets, namely: bracket 105, is provided with a vertical slot through which set screws 107 are passed and are screwed into the face of said carrier plate. A fixture 108 is secured to the face of said carrier plate with its opposed arms above and below the base portion of said bracket 105, as indicated in Figure 23. By means of set screws 109 and 110 in said arms the said bracket may be moved to precisely adjusted position vertically and in which said adjusted position it is made secure by tightening the set-screws 107.

Depending from a cross pin 112 in each of said brackets 105 and 106 is a hook of the conformation indicated in Figure 8 of the drawings.

Provided in the deck 31 at a location in parallelism with the said carrier plate 101 and perpendicularly below said hooks, is a transverse opening at which is secured an open rectangular frame 115 (see Figure 12) which communicates with a discharge chute 116.

Opposed structures substantial in weight and mass, preferably of cast iron, I designate as buff carriages. They consist of transverse elongated plates 121 and 122 embodying aligned bottom lugs 123—124 and integral exterior spaced vertical ribs 123a and horizontal ribs 125 as indicated in Figure 6, Figure 11 and Figure 12. The lug of each carriage is journaled on a shaft 126 that is rigidly secured in a support block 126a. The lugs 124 of each carriage are journaled on a shaft 127 that is rigidly secured in a support block 127a. Projecting from the arm of each of said end ribs is a horizontal pin 130, as shown in Figure 6 and in Figure 11.

The left hand end of one carriage (frontal carriage 121) and the right hand end of the other carriage (rear carriage 122) embodies at its upper portion, a divided pillow block with upper part

132 hinged on pin 133 and fastened by set screws 134.

The right hand end rib of one carriage (carriage 121) and the left hand end rib of the other carriage (carriage 122) embodies at its upper portion, a longitudinal extension 136 (see Figure 6) which in turn embodies aligned bearings 137 and 138. In the bearings 137 and 138 is journaled a shaft 140 upon which is secured a pulley 141. The shaft 140, as indicated in detail at Figure 17, is provided with a longitudinal tapered socket 143.

Each of two similar buffs consists of a mandrel 144, one end thereof formed to fit in said socket 143 and there secured by axial bolt 149 which extends through an axial bore therefor in said shaft 140, and the other end thereof, having a spindle 148 adapted to be seated in the lower half of pillow block 132. (See Figures 17-18.) The disks 145 of muslin or the like, together with intervening spacer washers 146 slipped on the mandrel are held securely clamped by a lock nut 147 at an end of each mandrel.

A lever 150 (see Figures 8 and 11) which embodies opposed lugs 151 and 152 (upper and lower respectively) in each of which is an adjusting screw 153, is fulcrumed on shaft 127 and is disposed in position adjacent the outer rib 123a of one of the carriages (carriage 121); the pin 130 of arm of said rib 123a being in position between the ends of said adjusting screws.

The lever 155 (see Figures 9, 11 and 12) which embodies opposed lugs 156 and 157 (upper and lower respectively) in each of which is an adjusting screw 158, is fulcrumed on the other shaft 127 and is disposed in position adjacent the outer rib 123a of the other carriage (carriage 122) the pin 130 of said rib being in position between the ends of said adjusting screws 157 and 158. The free end, each, of said levers 150 and 155, is directed downwardly. (As indicated in Figure 8.)

A lever 160 disposed between the ribs 124 of each carriage is fulcrumed on shaft 127. The free ends of said levers 160 are directed downwardly as indicated in Figure 9, to a point in registration with the plane of the centers of the free ends of levers 150 and 155. Interconnecting one of said levers 160 and the lever 150; and interconnecting the other of said levers 160 with the lever 155, at their free ends, is a cross shaft 162. Extending laterally from the free end each, of the levers 150 and 155 is a wrist 163 which embodies a pintle 166 upon which is journaled a roller 167. Each of the said central levers 160 embodies an upwardly directed bifurcated lug 165 provided with cross pin 166.

Air cylinders U and V pivotally supported by hangers 171 at the underside of deck 31 (pipes therefor designated 173 and 174) portions thereof being flexible (see Figure 32), have their piston rods connected as by links 176 to the said cross shafts 162. By control of the action of the pistons of these cylinders, the buff carriages may be swung toward each other and to advanced status (thereby placing the buffs in proximal positions) or may be swung from each other and to retracted status (thereby placing the buffs in remote positions).

Pivottally interconnecting the said carriages with the pins 166 of the lugs 165 of the central levers 160, are air cylinders W and X (see Figure 9). These cylinders, their functions, and the flexible piping 178 and 179 therefor will be presently referred to in diagram at Figure 32.

Journaled in pillow blocks 181 and 182 that are anchored each to the deck 31, is shaft 184 (right)

and upon which said shaft is secured pulley 186 which is integrated with pulley 187. Pulley 186 is connected by belting 188 to electric motor A located underneath the deck 31. (See Figure 1 and Figure 6.) Pulley 187 is connected by belting 189 to pulley 141.

Journaled in pillow blocks 191 and 192 that are anchored each to deck 31, is shaft 194 (left) (see Figure 12) and upon which said shaft is secured pulley 196 which is integrated with pulley 197. Pulley 196 is connected by belting 198 to electric motor B located underneath said deck. (See Figure 1 and Figure 12.) Pulley 197 is connected by belting 199 to pulley 142.

15 In a horizontal guideway provided in the housing which forms part of the lower portion of column 45 (at left hand side of machine) as indicated at Figure 13, a rack bar 201 rides slidably and in mesh with pinion 46a and at a plane above the axis of said pinion.

In a horizontal guideway of guide block 203 at left hand side of machine (see Figures 7, 13 and 15) is a slide 204 which is connected to said rack bar 201 as by an extension 205 and lug parts 206.

20 In a horizontal guideway provided in housing which forms a part of lower portion of column 55 (at right hand side of machine, as indicated by Figure 14) a rack-bar 211 rides slidably and it is in mesh with the pinion 56a at a plane below the axis of said pinion.

In a horizontal guideway of a guide block 213 at right hand side of machine (see Figure 14) is a slide 214 which is connected to said rack-bar 211 as by cap screws 215.

25 The said guide blocks 203 and 213 are so located that the slides 204 and 214 therein are in registration above and in alignment with the rollers 167 of the wrists 163 of the levers 150 and 155. (See Figure 11.) Each of these slides 204-214 (see Figures 15-16) is of longitudinally divided formation. The upper section at its outboard end embodies a downwardly directed head 204a provided with an aperture for the reception of an adjusting screw 228 and which is provided with set nuts 229.

30 Coincident with the upward movement of the rack-rods 44 (left) and rack-rods 54 (right) which operate in unison, there is rearward movement of left hand rack-bar 201 and there is forward movement of the right hand rack-bar 211.

35 For supporting in quantity, in position between the opposed buffs, the articles which are to be subjected to the action of the buffs, I provide a rack structure to accord with the type and form of article to be processed. For an article, as a fork, said rack structure is of form indicated in Figure 24. End plates 217, held in spaced opposed relation by longitudinal rods 218, are provided with pintles 219 which are adapted to be reposed removably in the hooks 113 and 114 of the carrier plate 101. Each of the confronting faces of the downwardly directed narrowed portions of said end plates, embodies a vertical flange 220, guideway block 221 and stirrup 222. Loose in said guideway block is latch bolt 223. Thin elongated cross bar 224 which is passed between tines of the fork (unfinished, its tines at their terminal portions being bridged by the usual web as indicated in Figure 27) one or the other of the said latch bolts 223 having been shifted to the broken line positions (see Figure 24), is disposed in position with its ends in the said stirrups 222 and against the flanges 220. The latch bolts are then

40 45 50 55 60 65 70 75 80 85 90 95 100

returned to lowered position the ends of same making the said cross bar 224 secure in its position and as it appears in Figure 24.

Whereas in the rack structure just described, the workholding element consists simply of a thin elongated cross bar, it will be understood that for the holding of articles as spoons or the like, a workholding structure of modified form, as indicated in Figures 28 and 29 is used.

To cause a varying of the distance between the opposed buffs in accordance with the variation of the distance between the opposed edges of the work carried by the said rack we provide on the bottom of each of the slides 204-214 (see Figures 13 and 14) a templet 225 with profile which is similar to the profile of said work. The said templet and which embodies a slide bar 225a is capable of being secured in precisely adjusted position on said slide with relation to the work, as by screw 228 carried by said slide bar and which is passed through head 204a of the slide and is there secured as by lock nuts 229.

To permit a floating action of the buffs whereby the buffs in responding to the dictation of the templets and while following the contour of the work, may exert a steady pressure against the work, the set screws 153-158 in the lugs of levers 150 and 155 respectively are adjusted so that there is a slight space 159 between the ends of said set screws and the pins 130 of the buff carriages.

Air cylinders W and X pivotally connected to the carriages 121 and 122 respectively (pipes therefor designated 178-179) portion thereof being flexible, have their piston rods connected by suitable pins to the lugs 165 of the levers 160, as hereinbefore referred to.

Reference is now had to the elevational view of the machine as in Figure 4, and to the diagram of the hydraulic system as in Figure 31. K designates a control valve (for speed of movement of face plate 88). L designates a control valve (for speed of movement of the cross beam 61). M designates a four-way pilot operating control valve actuated by trips (see Figure 19) whereby the desired length of stroke of the beam through control valve P is had. Trip 233 (upper) causes the beam to start upwardly. Trip 234 (lower) causes said beam to start downwardly. F designates a four-way piston type cam actuated valve (controlled by pilot valve M) and with flexible pipe connections 85, 86 to cylinder 81. R, S and Q designate operator operable regulation valves. O designates air controlled four-way valve which is inter-connected by pipe 177 to the compressed air system (see Figure 32) in which said air system is hand control valve G, reducing valve T, check valve N, regulation valve Y, air-pressure gauge regulator 180 and valve 183.

The several power units, valves and their connections indicated on the aforesaid hydraulic system and compressed air system, being of known construction and function, detailed illustrations or descriptions of same are deemed unnecessary.

The motors A and B, start button 243, stop button 244 and automatic switches 243a and 244a respectively, therefor; the motors C and E start button 245, stop button 246, automatic switches 245a and 246a respectively therefor, and the wiring therefor, are indicated in diagram Figure 33.

The broken lines in Figure 33 indicate the confines of the usual boxes 243b, 243b, 245b and 246b (see Figure 3) in which said automatic switches are contained. The said start buttons and said

stop buttons are indicated in Figure 1. The general wiring is carried in usual cables as in Figures 3 and 4 and the line wires L1, L2, L3, are carried in the usual cable (not shown) from source of current supply.

When G handle is moved from the neutral (Z) or closed position (see Figure 8) to position 1, the buffs are caused to be swung to remote positions indicated by the broken lines in Figure 8 where they rest.

When G handle is moved from position 1 to position 2, the said buffs are caused to be swung from said remote positions, to proximal positions indicated by the solid lines in Figure 8, for work. At the same time, the cross beam 61 and the face plate 88 will have been caused to be set in motion.

When G handle is then moved from position 2 back to position 1, the buffs are caused to be moved to retracted or remote positions, the cross beam and face plate continuing in operation.

For describing a typical performance of my new machine an article, for example, an unfinished fork of conventional type and form as indicated at Figure 27 is shown. The contour templets 225 (see Figures 13, 14 and 15) each with profile identical with the side contours of the said article, are in readiness, and same are secured as by cap screws 216, to the slides 204 and 214.

Valve Q is opened. Valve G is in closed status, its handle being in neutral or Z position, as in Figure 8.

In making ready for placing the machine in operation, the carriages are manually swung from the broken line or remote positions (see Figure 8) to the solid line or proximal positions. Then by adjusting the screws 153-158 said carriages are set so that the distance between the buffs is in accord with the minimum of the various distances between the opposed edges of the work. Then by adjusting the screws 229 (see Figure 15) the templets are set at precisely true positions.

The work rack, with its hanger bar 224 loaded with unfinished forks closely arranged in successive order, end to end of said bar, is then manually placed in position with its pintles 219 in the hooks 113 and 114 of the carrier structure. By adjusting the screws 103 and 110 of the fixture 188 the said rack is poised in parallelism with the buffs, after which the set-screws 107 are tightened, thereby securing the bracket 105 in its adjusted position.

The length of the stroke and the speed of movement of the cross beam having been determined with regard to the contours of the work, adjustment of the trips 233 and 234 are then made. Adjustment also is made at valve K in accordance with the desired speed of movement of the face plate 88.

G handle, as hereinbefore stated, is at zero or neutral position. The cross beam is at an end of its stroke. Face plate 88 is at an end of its stroke.

Coincident with the rotating of the buffs, the vertically reciprocable movement of the cross beam, the transversely reciprocable movement of the carrier structure (including the face plate and carrier plate), the work rack and the work carried thereby, and with the travel of the templets, there is accomplished a follower action of the carriages while in their proximate relation whereby there is a varying of the distance between the buffs in conformity with the flowing contours of the opposed edges of the work.

For obtaining the movements above referred to,

and for obtaining the coordination and control of said movements we provide the combination and arrangement of parts, as follows:

Secured to one of the frame uprights, namely: upright 41 (see Figure 19) is the four-way pilot valve M (hydraulic, hereinbefore mentioned) for stroke of beam, with dogs M1 and M2. Carried by said cross beam at its rear side is an upright bar 231 provided with vertical slot 232 in which are retained adjustable trips 233 and 234 that are in the path traversed by said dogs respectively.

Mounted on the deck 31 is the hydraulic valve F hereinbefore mentioned (see Figure 7) its piston actuated by a cam 235 driven by shaft 236 which is geared as by gear wheels 237 and 238 to 15 ratiomotor E, and which said valve F gives intermittent action of the face plate 88.

Secured at position underneath the said deck is electric motor C (see Figure 5) its shaft coupled as at 240 to the shaft of oil pump D, the inlet pipe 241 of which said pump leads from the source of supply namely: oil tank 242 located in the lower portion of the machine frame. This pump supplies the energy for the entire hydraulic line. J designates a relief valve, balanced piston type, for controlling the pressure in the hydraulic circuit.

Operation

Push at start button 245 (see Figure 33) energizes motor C and ratiomotor E. By action of the oil through vertical cylinder 51 and by-pass valve L the cross-beam is caused to move up and down; and the face plate 88, by valve F, is caused to move crosswise reciprocatively.

Now, upon moving handle of control valve G to position 1 (see Figure 8) and the consequent release of air pressure into lines 173 (see Figure 32) and to cylinders U and V, the carriages are caused to swing the buffs to and to maintain them in the working or proximal positions. Push at start button 243 energizes motors A and B and establishes the driving of the buffs in the confronting directions as indicated by the arrows in Figure 8. Motors A and B may be deenergized by a push of stop button 244. Motors C and E may be deenergized by push of stop button 246.

In the procedure of buffing, the action of carriages is had through the functioning of the levers 150—155.

Incident to the functioning of the said cross beam 61, and the functioning of said face plate 88, the path followed by the work, namely: the quantity of articles carried by the work-rack, is elliptical, and the effect of the buffs upon said work is a brushing of the ware equally longitudinally and also transversely of said ware. The refuse, which is incidental to said brushing, escapes downwardly and is passed through the space bounded by the wall plates 121—122 and the cheek plates 117—118 of the carriages, and is emitted through discharge chute 116.

After the ware will have been caused to traverse the zone between the buffs during a period of about thirty seconds, the desired finish will have been imparted to the ware.

The operative then returns the handle of valve G to neutral position whence through the action of the air through lines 173 and 174 and cylinders U and V the carriages are caused to swing to remote status and at rest, the driving of the buffs being not interrupted. The operative then removes the loaded work-rack and its finished ware simply by lifting said rack from the hooks of the carrier structure. In the meantime another work-

rack loaded with unfinished ware is placed in connection with the carrier structure in the manner as hereinbefore described. G handle is then moved to position 1 whence the carriages are swung toward each other and the buffs brought to working position engaged with the work.

At any time during the procedure of buffing, regulation may be had by valve R to vary the speed of movement of the cross beam with relation to the character and contour of the work. Also regulation may be had, by valve S, to vary the speed of the cross movement of the face plate with relation to the character and contour of the work.

All moving parts of the machine are so coordinated that once the necessary adjustments are made to accommodate the ware to be handled, the operation of the machine proceeds without need of special attention and it performs its functions automatically. The hood structures shown constitute protective and safety guards against personal injury, and same contribute to maintenance of cleanliness. Suitable lubrication of all working parts is provided as by conventional means and not shown. At all times during operation of the machine the buffs are under such control that while the desired degree of buffing pressure, as indicated by air pressure gauge T1 is had, said pressure is cushioned by the reducing valve T, and at the same time the distance between the buffs is caused to vary in accordance with the contours of the work which is being operated upon.

Whereas, my new machine as it is herein illustrated and described constitutes a practical embodiment of my invention, it will be understood that I do not limit myself to the exact details of construction shown and explained since manifestly the same may be modified without departing from the spirit and principle of the invention as defined in the claims.

What I claim as my invention is:

1. A machine of the kind described comprising, in combination, a frame, a cross beam supported by and vertically reciprocable on said frame, a carrier structure supported by and which is horizontally reciprocable on said beam, means to operate the beam, means to operate the carrier structure, a work-holding rack supported by the carrier structure, opposed carriages pivotally mounted in position below the carrier structure and in parallelism with the rack, each carriage being equidistant from the perpendicular plane of said rack, buffs journaled for rotation on said carriages, means to drive the buffs, guideway structures, slides thereon, profile cams secured to the slides, power transmitting devices interconnecting the cross beam and said slides, to move said slides reciprocatively, and power transmitting devices interacting between the cams and said carriages.

2. A machine of the kind described comprising, in combination, a frame, a cross beam supported by and vertically reciprocable on said frame, a carrier structure supported by and which is horizontally reciprocable on said beam, means to operate the beam, means to operate the carrier structure, a work-holding rack supported by the carrier structure, opposed carriages pivotally mounted in position below the carrier structure, and in parallelism with the rack, each carriage being equidistant from the perpendicular plane of said rack, buffs journaled for rotation on said carriages, means to drive the buffs, guideway structures, slides thereon, profile cams

11

secured to the slides, power transmitting devices interconnecting the cross beam and said slides, to move said slides reciprocatively, said devices including a rack-rod directed downwardly from each end portion of the cross beam, two pairs of pinions journaled on bearings supported by the frame, each of said rack-rods being in mesh with a pinion of each of said pairs, power transmitting devices interacting between the cams and said carriages, said devices including rack-bars connected with said slides, each of said rack-bars being in mesh with the other pinion of each of said pairs, follower levers fulcrumed adjacent to and movable to engagement with said carriages, the free ends of said levers being engaged by said cams, and devices manually operable to adjust the distance between the carriages and said levers.

3. A machine of the kind described comprising, in combination, a frame, a cross beam supported by and vertically reciprocable on said frame, a carrier structure supported by and which is horizontally reciprocable on said beam, means to operate the beam, means to operate the carrier structure, a work-holding rack supported by the carrier structure, opposed carriages pivotally mounted in position below the carrier structure and in parallelism with the rack, each carriage being equidistant from the perpendicular plane of said rack, buffs journaled for rotation on said carriages, means to drive the buffs, guideway structures, slides thereon, profile cams secured to the slides, power transmitting devices interconnecting the cross beam and said slides, to move said slides reciprocatively, said devices including a rack-rod directed downwardly from each end portion of the cross beam, two pairs of pinions journaled on bearings supported by the frame, each of said rack-rods being in mesh with a pinion of each of said pairs, power transmitting devices interacting between the cams and said carriages, said devices including rack-bars connected with said slides, each of said rack-bars being in mesh with the other pinion of each of said pairs, follower levers fulcrumed adjacent to and movable to engagement with said carriages, the free ends of said levers being engaged by said cams, and devices manually operable to adjust the distance between the carriages and said levers, means operable to control the carriages in the interim during their movement through said distance.

4. A vertical finishing machine comprising in combination, an upright frame, a cross beam supported by and which is vertically reciprocable on said frame, a work-carrier structure mounted on said beam and which is transversely reciprocable thereon, means to move the cross beam, means to control the speed of movement of said beam, means to limit the length of stroke of said beam, means to regulate the beam moving means, means to move the carrier, means to control the speed

12

of the carrier mover means, means to regulate the carrier mover means, opposed carriages mounted in position below said carrier structure, buffs journaled on the carriages, means to drive the buffs in confronting directions, guideway structures mounted on the frame, a profile templet cam slidable in each guideway structure, power transmitting connections between the cams and the said cross beam, and follower members interengaged with the carriages to move same, said follower members being engaged with said cams.

5. A vertical finishing machine consisting of a frame embodying a standard, a cross beam slideable vertically on said standard, a face plate slideably and horizontally retained on said beam, means to reciprocate the beam, means to reciprocate the face plate, a carrier plate connected to the face plate and adapted to be set in and held at adjusted position vertically thereon, suspensor devices projected from the carrier plate, an elongated work-rack removably attached to said suspensor devices, carriages arranged in parallel opposed relation and equidistant from the vertical plane of said suspensor devices, a buff mounted for rotation on each carriage, means to rotate the buffs, a lever with its weight arm engageable by but spaced a short distance from each carriage, said levers being operable to move said carriages toward each other through said short distance and the carriages being capable of retreating, devices to predetermine the said short distance, said devices interacting between the carriages and said levers to permit the retreat of said carriage within the range of said short distance, guideways, slides therein, power transmitting devices interconnecting the cross beam and said slides to move said slides reciprocatively and in opposed directions, profile cams carried by said slides, said cams being engageable by the free ends of the levers, devices interacting between said levers and said carriages to permit yield of the carriages retractively, means to regulate the degree of said yield, means to determine the length of stroke of said beam, means to vary the length of stroke of the face plate, and means to drive the buffs.
